UNITED STATES PATENT OFFICE.

STEPHEN TOTH, OF OLYPHANT, PENNSYLVANIA.

ATTACHMENT FOR ROCKING-CHAIRS.

Application filed January 23, 1922. Serial No. 531,224.

To all whom it may concern:

Be it known that I, STEPHEN TOTH, a citizen of the United States, residing at Olyphant, in the county of Lackawanna and State of Pennsylvania, have invented certain new and useful Improvements in Attachments for Rocking-Chairs; and I do declare the following to be a full, clear, and exact description of the invention, such as will enable others skilled in the art to which it appertains to make and use the same.

This invention relates to an improved attachment for rocking chairs, having more particular reference to pneumatic cushions for attachment to the undersides of the rockers for directly bearing on the floor to prevent undue slipping of the chair, marring or injury to highly polished floors, to eliminate undesirable squeaking noises, and to absorb to a certain extent, shocks and jars brought about when the chair is placed on an uneven floor.

The principal object of the invention is to generally improve upon attachments of this class by providing one which is simple and inexpensive and is merely composed of two parts, namely a pneumatic cushion and a clamping frame, these parts being of such construction that they insure effective results and permit quick application and removal of the cushion whenever necessary or desired.

In the accompanying drawing forming a part of this specification and in which like numerals are employed to designate like parts throughout the same:

Figure 1 is a side elevational view of a chair rocker provided with an attachment constructed in accordance with this invention.

Figure 2 is a central longitudinal sectional view through Fig. 1.

Figure 3 is a bottom plan view of Fig. 1.

Figure 4 is an enlarged transverse section taken substantially on the plane of the line 4-4 of Fig. 3.

In carrying out the invention, I make use of a strong and durable elongated pneumatic cushion or tube 1 having a flat upper side 2 to directly bear against the underside

of the rocker R. A marginal flange 3 entirely surrounds this flattened portion of the cushion and the combined width of the flanges and cushion is equal to the width of the rocker and when in position, the cushion appears as clearly shown in Figure 4. Entirely surrounding the inflated portion of the cushion and directly engaging the underside of the flange 3, is an elongated clamping frame 4, the side and end portions of which are of a width equal to the width of the flange. Fastenings 5 pass through this frame and flange and into the rocker and serve to secure the parts in position on the latter. It is yet to be pointed out that a conventional form of tire valve 6 communicates with the inflation chamber of the cushion and extends through an opening formed in the rocker to a point to permit attachment of an ordinary tire pump thereto for filling the cushion with the desired amount of air pressure.

In practice, both of the rockers of the chair will be equipped with these pneumatic cushions and when the latter are in place, the inflated or body portion will directly bear on the floor and prevent direct contact of the rocker with the latter. Consequently, if the floor is highly polished, it will not be marred as is the case when the chair is permitted to move unduly about in different directions when rocking. Furthermore, the attachment will greatly add to the comfort of the chair by absorbing many of the shocks and jars caused by uneven floors. These and other advantages and features of the invention have doubtless been made apparent from the foregoing description. Also the invention itself and application is doubtless understood. Therefore, a more lengthy and detailed description is thought unnecessary.

Although the attachment has been shown and described as being used more particularly on rocking chairs, it is to be understood that it will serve equally well on cradles or the like.

I claim:

A rocking chair tire comprising a tube semi-circular in cross-section and having a

flat inner rocker-engaging wall having extended side and end portions providing a continuous border flange, and an open frame fitting snugly about the tire and resting flat against said flange whereby fasteners may be passed through the frame and flange to secure the tire against a rocker, said tube

being provided with an inflating neck extending through its flat inner wall for extending upwardly through a rocker. ¹⁰

In testimony whereof I have hereunto set my hand.

STEPHEN TOTH.
